UNITED STATES PATENT OFFICE.

FRANKLIN D. SICKLES, OF TOLEDO, OHIO, ASSIGNOR, BY MESNE ASSIGNMENTS, TO CARL H. KELLER, OF TOLEDO, OHIO.

CARPET-LAYING TOOL.

SPECIFICATION forming part of Letters Patent No. 773,428, dated October 25, 1904.

Application filed October 29, 1903. Serial No. 179,016. (No model.)

To all whom it may concern:

Be it known that I, FRANKLIN D. SICKLES, of Toledo, county of Lucas, and State of Ohio, have invented certain new and useful Improvements in Carpet-Laying Tools; and I do hereby declare that the following is a full, clear, and exact description of the invention, which will enable others skilled in the art to which it appertains to make and use the same, reference being had to the accompanying drawings, and to the figures of reference marked thereon, which form part of this specification.

My invention has reference to a carpet-laying tool; and it has for its object to provide a simple, compact, inexpensive, and highly-efficient household tool capable of being advantageously operated in various ways.

To this end the invention embodies the novel combination and arrangement of component parts and details of construction hereinafter described, and pointed out in the claims.

While the invention is susceptible of some modification, the accompanying drawings show, and I shall now hereinafter describe in connection therewith, what is now conceived to be the preferred embodiment of the same.

In the drawings, Figure 1 is a perspective view showing my improved tool. Fig. 2 is a top plan view of the same. Figs. 3 and 4 are elevations, respectively, of opposed sides of the tool.

The tool is preferably cast in one piece, being of cast-steel or other suitable material. It consists, essentially, of a hammer comprising a handle 2 and a flattened substantially rectangular head 1, having the plane striking-surface 4 and being further provided along its lower front edges with a series of teeth 10. Projecting forwardly from the outer face of the head and lying in a plane parallel to the striking-surface are claws 5, having the form of the ordinary tack-puller. As handle 2 adjoins the head at the diagonally opposite corner and striking-surface 4 is somewhat elongated, a powerful leverage is effected, the intermediate corner 4^a of the head acting as a fulcrum. The teeth and striking-surface are formed upon adjoining

sides of the rectangle. Hence while laying 50 a carpet by means of this tool it will be possible to put the hammer in position either for stretching or tacking the carpet by merely turning the handle a quarter-revolution. Thus the material may be stretched by a forward motion of the head and a tack quickly driven to secure the position so obtained, the whole operation being performed with much more expedition than if two tools were employed or the parts differently arranged upon 55 the head.

In stretching carpets with this tool it is usual to drive a tack to hold the material until the desired degree of tension has been obtained. Then a rapid quarter-revolution 65 brings the claws in operation for removing the temporary tack, after which without changing the position of the tool the permanent tack is driven home.

It is to be noted that the handle is inserted 70 to one side of the center of the head, forming a prolongation of the face opposite the striking-surface. I consider this a very important feature, as it throws the weight of the head entirely on the side of the handle 75 toward the striking-surface and claws and greatly facilitates the rapid quarter-revolution that changes the horizontal to the pendent position of the head.

The outer edge of the head not occupied by 80 teeth 10 may be raised and sharpened, as at 11, to be used for various purposes, such as scraping. Upon the side of the rectangle opposite face 4 I have shown an extension 6, pointed at 7 and having sharpened edges 8 85 and 9, the edge 8 adapting the tool, if desired, for use as a can-opener, and the edge 9 permitting it to be advantageously employed as a meat-tenderizer. The end of the handle may be sharpened, as at 3, adapting the tool for 90 use as an ice-pick. The head is provided with a tapered slot 12, which serves both to cheapen the manufacture of the tool and to adapt it for use as a wrench for nuts of varying sizes.

Having described my invention, what I 95 claim, and desire to secure by Letters Patent, is—

1. A carpet-laying tool comprising a han-

- dle and a head having a plane striking-surface and a series of teeth arranged substantially at right angles thereto, the center of said head being intermediate the striking-surface 5 and the point of attachment of the handle.
2. A carpet-laying tool comprising a handle and a head having a plane striking-surface and a series of teeth arranged substantially at right angles thereto and projecting oppo- 10 sitely from the handle, the center of said head being intermediate the striking-surface and the point of attachment of the handle.
3. A carpet-laying tool comprising a handle and a rectangular head having a striking- 15 surface at one side of the rectangle and a row of projecting teeth upon one of the adjoining sides thereof, said handle forming a prolongation of the side of the rectangle opposite the striking-surface.
4. A carpet-laying tool comprising a handle and a rectangular head having a striking- 20 surface at one side of the rectangle and a forwardly-projecting row of teeth upon the lower edge of the adjoining side opposite the han- 25 dle, said handle forming a prolongation of the side of the rectangle opposite the striking-surface.
5. A carpet-laying tool comprising a handle and a head having a plane striking-surface, a series of teeth arranged substantially 30 at right angles to the striking-surface, and tack-pulling claws projecting forwardly from the head and lying in a plane parallel to the striking-surface.

6. A carpet-laying tool comprising a han- 35 dle and a head having a plane striking-surface, a series of teeth arranged substantially at right angles to the striking-surface, and tack-pulling claws projecting forwardly from the head and lying in a plane parallel to the 40 striking-surface, the center of said head being intermediate the striking-surface and the point of attachment of the handle.

7. A carpet-laying tool comprising a rec- 45 tangular head having a striking-surface at one side thereof, a row of forwardly-projecting teeth upon one of the adjoining sides, and tack-pulling claws at the corner of said sides; combined with a handle having its point of attachment at the corner diagonally oppo- 50 site from said claws.

8. A carpet-laying tool comprising a rec- 55 tangular head having an elongated striking-surface at one side thereof, a row of forwardly-projecting teeth upon one of the adjoining sides, and tack-pulling claws at the corner of said sides and forming a prolongation of the striking-surface; combined with a handle projecting from the corner diagonally 60 opposite the claws and forming a prolongation of the side opposite the striking-surface.

In testimony that I claim the foregoing as my own I affix my signature in presence of two witnesses.

FRANKLIN D. SICKLES.
